UNITED STATES PATENT OFFICE.

EMERY J. BROOKS, OF PHILADELPHIA, PENNSYLVANIA.

COMBUSTION OF FUEL.

SPECIFICATION forming part of Letters Patent No. 225,793, dated March 23, 1880.

Application filed November 10, 1879.

To all whom it may concern:

Be it known that I, EMERY J. BROOKS, of Philadelphia, Pennsylvania, have invented a new and useful Improvement in Preventing 5 the Formation of Smoke in the Combustion of Fuel, of which the following is a specification.

The object of my invention is to so burn bituminous coal or other smoke-producing fuel that the formation of smoke will be prevented 10 or materially modified and a more effective combustion of the fuel insured. This object I attain by combining with the fire-box of a furnace a roasting-chamber inaccessible to the products of combustion, and having a movable 15 bottom plate, whereby the fuel may be subjected to a preliminary roasting operation to drive off the volatile gases, and, when coked, may be readily dumped onto the mass of incandescent fuel in the furnace, all as herein- 20 after more fully set forth.

In the accompanying drawings, Figure 1 is a longitudinal section of part of a boiler of the locomotive type having a furnace constructed for carrying out my invention; Fig. 2, a trans- 25 verse section of the same on the line 1 2, and Fig. 3 a view of a modification.

In the ordinary manner of burning fuel the volatile gases are evolved so rapidly that they absorb the heat from the incandescent carbon 30 and prevent the entire combustion of the latter, thereby leaving a portion of the carbon free in the form of smoke.

The aim of my invention is to prevent as far as possible the liberation of such free carbon, 35 which, being in the amorphous state, is practically incombustible at ordinary furnace temperatures.

In the drawings, A represents part of the shell of the boiler; B, the usual flue-tubes; D, 40 the main grate, and E the ordinary fire-door. Across the upper portion of the fire-box, at a distance from the tube-sheet a, extends a water-space partition, F, which serves to divide said upper portion of the fire-box into two 45 chambers, I and J, the former communicating with the main combustion-chamber K through a passage, b, and the chamber J being separated from the said combustion-chamber K by a plate, d, which is pivoted in the center and can 50 be rotated from outside the boiler by means of a

crank, f, or by any other suitable means. An automatic device operating at proper intervals may, for instance, be employed. Access to the chamber J is afforded by means of an opening, e, and communication between the chambers I and J is afforded by means of a series of tubes, g, passing through the hollow partition F. Air gains access to the chamber I through lateral openings m, which may, if desired, be provided with suitable dampers or 60 valves, whereby the entrance of air can be regulated.

The operation of the furnace is as follows: The fuel upon the grate D being kindled, the chamber J is partially filled with fuel and the 65 opening e closed. The heat from the products of combustion in the chamber K causes the evolution of the volatile gases from the fuel in the chamber J, these gases passing through the tubes g into the chamber I, where they 70 mingle with the heated products of combustion from the chamber K, and are ignited thereby prior to passing through the flues B. The lateral openings m supply the proper amount of air to the chamber I in order to effect 75 this combustion of the gases. When the volatile gases have all been driven off from the fuel in the chamber J by the roasting process to which said fuel has been subjected, the plate d is turned so as to dump the fuel 80 (now in the form of coke) onto the mass of fuel on the main grate D, the plate d being then restored to its original position and a fresh supply of fuel introduced into the chamber J, from which, after being roasted, as above 85 described, it is dumped onto the mass of fuel below, the latter being thus constantly supplied with coked fuel.

By thus subjecting the fresh fuel to a preliminary roasting operation, so that the volatile gases are evolved therefrom and combined with the heated products of combustion at a point remote from the surface of the incandescent fuel in the combustion-chamber, the liberation of free carbon in an amorphous state can 90 not take place, and the formation of smoke is thereby prevented.

It is important in carrying out my invention that the fuel which is being roasted shall be preserved from direct contact with the pro- 95 100

ducts of combustion; otherwise said fuel will become ignited, and the object which I am aiming at will be frustrated.

In Fig. 3 I have shown a modified construction of furnace, in which the chamber J is contracted at the bottom and the partition F so constructed as to leave a passage at the top for the gases from said chamber J.

I claim as my invention—

10 1. The combination of the fire-box of a furnace with a roasting-chamber located in the upper portion of the main fire-chamber, and constructed, as described, so as to prevent the access of the products of combustion thereto, 15 but provided with a movable bottom plate,

whereby its contents may be dumped onto the mass of fuel on the fire-grate, all substantially as described.

2. The combination of the fire-box of a furnace with a transverse partition, F, the openings g therein, and pivoted plate d, inclosing a chamber in the upper portion of the main fire-chamber, all substantially as set forth.

In testimony whereof I have signed my name to this specification in the presence of two sub- 20 25 scribing witnesses.

EMERY J. BROOKS.
